2,453,111

RADIUS ATTACHMENT FOR LATHES

Allen M. Bell, Jr., Philadelphia County, Pa.

Application November 22, 1946, Serial No. 711,766

2 Claims. (Cl. 82—11)

(Granted under the act of March 3, 1883, as
amended April 30, 1928; 370 O. G. 757)

1

The invention described in the following specification and claims may be manufactured and used by or for the Government for governmental purposes without the payment to me of any royalty thereon.

This invention relates to a lathe or an attachment for a lathe which may be easily mounted upon the usual lathe bed and, more particularly, relates to a device for cutting a curved surface having a large radius of curvature on a work piece having a small diameter.

In all the prior devices, with which I am familiar, for cutting a curved surface in the shape of a circular arc, the cutting tool is pivotally mounted for manual or mechanical turning movement about a pivot mounted on the cross head or compound rest of the lathe. Obviously, in cutting curved surfaces of large radius, the distance must be very large between the tool and the pivot or axis about which it turns and upon which it is supported. This gives rise to a weak support for the cutting tool, which is undesirable.

Accordingly, it is an object of the present invention to provide a lathe or lathe attachment having the following features. The cutting tool is mounted in the customary tool holder supported on the compound of the lathe for straight-line movement lengthwise and crosswise of the lathe in two mutually perpendicular directions. A stationary pivot is provided which either forms an integral part of or may be adjustably secured in any desired fixed position to a stationary part of the lathe. A link, whose length is equal to the radius which it is desired to cut, is pivotally mounted on this stationary pivot and pivotally connected to the tool holder. The tool holder is driven, either mechanically or manually, along one straight line and is free to slide in a perpendicular straight line so that the tool holder and the tool carried thereby move with a translatory movement in a path which is a portion of a circle or arc.

Another object of the present invention is to provide a radius-cutting lathe or lathe attachment, which may be easily substituted for or applied to the ordinary turning lathe, and which is capable of making accurate arcuate cuts, in addition to performing all the functions of the ordinary lathe compound.

A further object is to provide such a radius-cutting device which is easily adjustable for making arcuate cuts of different radii.

A still further object of this invention is to provide a lathe tool, which will accurately cut a circularly curved surface and which will later

2

exactly reproduce or duplicate this curved surface, and which will cut a concave curved surface and a convex curved surface which surfaces exactly interfit and mate together.

5 Finally, it is an object of the present invention to incorporate all the foregoing advantageous features in a simple, compact and inexpensive lathe or lathe attachment which may be easily operated and which requires no additional space.

10 These and other objects are attained by the improvements comprising the present invention, which may be stated in general terms as including a lathe bed having sliding ways on it, a tool holder slideable longitudinally and transversely of said ways, a fixed pivot mounted on a stationary part of the lathe, and a link which is the length of the desired radius, which is to be cut, and is pivotally mounted on said fixed pivot and pivotally attached to said tool holder so that the tool holder is constrained to move in a circularly curved path of the desired radius.

15 For a further exposition of this invention reference may be had to the annexed specification and accompanying drawings.

20 25 In the drawings:

Fig. 1 is a perspective view showing the lathe attachment.

Fig. 2 is a view in vertical cross section showing a modified form of radius-limiting link which is 30 adjustable.

Fig. 3 is a top or plan view of the headstock end of the lathe and the adjacent parts.

Fig. 4 is a view in front elevation of the parts at the headstock end of the lathe.

35 Fig. 5 is a vertical longitudinal cross section on zig-zag line 5—5 of Fig. 3 on an enlarged scale.

Fig. 6 is a vertical transverse cross section on an enlarged scale on line 6—6 of Fig. 4.

40 Fig. 7 is a vertical transverse cross section on an enlarged scale on line 7—7 of Fig. 4.

Fig. 8 is a vertical longitudinal cross section on an enlarged scale on line 8—8 of Fig. 3.

45 Fig. 9 is a top or plan view showing a modification of a portion of the headstock and of the lathe and the adjacent parts.

Fig. 10 is a front elevation of the parts at the headstock end of the lathe as shown in Fig. 9.

Fig. 11 is a transverse vertical cross section on 50 line 11—11 of Fig. 9 as viewed in the direction of the arrows.

One embodiment of this invention is as follows. A turning lathe has, on the upper surface of its bed, a pair of longitudinally extending ways 55 10—11 at one end of which is the headstock 12.

Power is applied to the headstock either by means of a self-contained electric motor, a cone pulley for receiving a belt, or other convenient conventional device. Rotatably mounted in headstock 12 is a work receiving chuck 13 in which is firmly secured a rod WW (as shown in Figs. 3 and 4) or other work piece W (as shown in Fig. 1) of small diameter, on which a circularly curved surface of long radius is to be turned. Slidably mounted on ways 10 and 11 is a carriage which includes compound 14, which is movable longitudinally of the lathe bed in one straight line, and which is also movable transversely of the lathe bed in a straight line at right angles to its longitudinal movement. The carriage which includes compound 14 can be moved manually longitudinally by a handwheel 60 or mechanically by means of a power driven lead screw 15. Compound 14 can be driven transversely of the lathe bed by means of manually operable handwheel 16, or can be mechanically driven by a connection (not shown) from the lead screw 15. Upon the compound 14 is mounted a cross slide 17 having groove 18 in it. In groove 18 is secured the tool holder 19 which carries the tool bit 20 having at one end of it a cutting tool 21.

Referring to Fig. 1 for a convenient showing, anchor clamp 22 engages the under side of the slide ways 10 and 11. Through anchor clamp 22 passes anchor clamp bolt 23 which is secured by means of a nut 24 to anchor base 25 whose lower face is suitably shaped to interfit with the slide ways 10 and 11. To the upper surface of anchor base 25 is secured anchor bed 26 having in its upper surface a transversely extending groove 27.

Figs. 5, 7 and 8 show in greater detail the anchor bed 26 having groove 27 in it into which extends a ridge 28 forming part of a clamp bracket 29 in which is screw threadedly engaged a bracket-adjusting screw 30 having a protruding head 31 and a smooth portion 32 intermediate two collars. Bracket-adjusting screw 30 engages with an inverted slot in a part attached to adjustable bracket 33 which is slidably transversely of clamp bracket 29 and longitudinally of the lathe. A pair of bracket securing screws 34 each has at its upper end a nut 35 by means of which the clamp bracket 29 and the adjustable bracket 33 may be firmly secured in a selected position along the groove 27 in the anchor bed 26. At one end adjustable bracket 33 has a hole 36 through it in which is mounted a pivot pin 37 having an enlarged head 38 knurled or otherwise formed to be grasped by the hand so that pin 37 is readily inserted into or removed from hole 36.

A link 39 has in it holes, each adjacent one of its ends, whose centers are spaced apart by a distance exactly equal to the radius which it is desired to cut. Pin 37 passes through one of the holes in link 39 as well as through hole 36 and pivotally secures link 39 to adjustable bracket 33.

Cross slide 17 has a pair of bolts 40 secured to it. Mounted on one of these bolts 40 is a compound clamp 41 which has a perforation in it through which the bolt 40 passes. The compound clamp has a notch 42 in one face arranged to fit over the corresponding shoulder of the cross slide 17. Nut 43 on bolt 40 secures the compound clamp 41 to the cross slide 17. Compound clamp 41 also has a hole 44 passing through it, in which is located a pivot pin 45 having a knurled or like head 46. Pin 45 also passes

through the other hole in link 39 and serves to pivotally secure the link 39 to the cross slide 17 and consequently to the compound 14 and to the tool holder 19.

The operation of the radius cutting device of this invention is as follows. Assume that it is desired to cut a concave, circularly curved surface in the work piece W shown in Fig. 1. The first step is to select a link having a distance between the centers of the holes therein equal to the radius which is to be cut. In readying the lathe for this operation, the cross feed nut (not shown) in the lathe is disengaged and removed if possible. This leaves the compound 14 (and the parts carried thereby) free to slide back and forth transversely of the bed of the lathe. The compound 14 (and consequently the cutting tool 21 carried by it) is fed longitudinally of the lathe, this feed being either manual or mechanical. The work piece W is then placed in the chuck 13 of the lathe, and the tool bit 20 is placed in the tool holder 19 and secured therein. The anchor clamp 22 is placed beneath the ways 10 and 11. The anchor base 25 is mounted on the ways 10 and 11 above the anchor clamp 22, and the anchor clamp bolt 23 is passed through suitable holes in the anchor base 25 and the anchor clamp 22. Nut 24 is then mounted on the anchor clamp bolt. Anchor bed 26 is located so as to project towards the operator's side of the lathe, in this case, since it is desired to make a concave cut. In case it is desired to make a convex cut, the anchor bed is arranged to project toward the back or far side of the lathe bed away from the operator. The clamp bracket 29 and the adjustable bracket 33 are then secured in position on the anchor bed 26 by means of the bracket securing screws 34 and the cooperating nuts 35. The nut 43 is removed from the compound of the lathe and the compound clamp 41 is fastened in place by passing the bolt 40 through the hole in the compound clamp 41 so that the notch 42 fits against a shoulder on the cross slide 17. Tightening nut 43 then secures the compound clamp 41 tightly to the compound 14 and provides a motion-transmitting connection to all the parts carried by the compound 14, including the cutting tool 21. The selected link 39 is then placed so that the holes in it are aligned with the holes in the adjustable bracket 33 and in the compound clamp 41. Pin 37 is slipped through the holes in the adjustable clamp 33 and one hole in the link 39. Pin 45 is slipped through the holes in the compound clamp 41 and the other hole in link 39. Link 39 is thus pivotally secured between the adjustable bracket 33 and the compound clamp 41. In case it is desired to cut a curved surface tangent to a surface of work piece W, the anchor assembly is now slid along ways 10 and 11 of the lathe until link 39 is parallel with the axis of the anchor assembly which extends transversely or crosswise of the lathe. This insures that the axis of the pivot pin 37 is located in the proper position. Nut 24 and nuts 35 are then tightened to secure the anchor assembly, the clamp bracket 29, and the adjustable bracket 33 firmly in their proper positions. Before the nuts 35 are tightened, the adjustable bracket 33 may be moved relative to the clamp bracket 29 a small amount by turning the bracket-adjusting screw 30 by means of its head 31. The cutting tool 21 is then backed off from the work by a suitable movement of cross slide 17. The compound 14 is moved longitudinally of the lathe

and consequently longitudinally of the work piece W until the cutting tool 21 is opposite that portion of the work piece W where it is desired to begin the cut. The cutting tool 21 is then fed towards the turning axis of the lathe to the desired depth of the first cut. Power is then applied to the lathe to start the rotation of the work piece W. The compound 14 and consequently all the parts carried by it, including the cutting bit 21, are fed longitudinally of the lathe, either manually or mechanically. Since the compound is free to slide transversely of the lathe but is held about the center of pin 37 as a pivot, cutting tool 21 moves with a translatory movement along a path which is a portion of the circumference of a circle whose radius is the distance between the centers of the pins 37 and 45. In this way the desired radius is generated. This feed is continued until the cutting tool 21 runs off the work. If a mechanical feed has been employed, it is then disengaged and the compound 14 (and the parts carried thereby) are turned back to the starting point. The cutting tool 21 is fed in towards the turning center of the lathe a distance equal to the desired depth of the second cut and the whole process repeated again and again in a series of cuts until sufficient metal has been removed from the work piece W to leave a curved surface of the desired radius. In case the set-up has been made so that the cutting tool 21 (and consequently the curved surface cut) is tangential to the surface of the work piece W, the final cut will terminate at this point of tangency.

Fig. 3 shows particularly that this device operates most efficiently when the feed is substantially at right angles to the long axis of the link 39. When the direction of the feed and the axis of the link 39 coincide, the device has a dead center and will not operate at all. As a practical matter, the device operates best when the angle between the direction of feed and the axis of the link 39 is greater than ten degrees. This efficiency progressively increases as the angle increases, being greatest, as has been stated, at ninety degrees. It will thus be seen that it is not practical to cut a complete hemisphere with this device, although it can be done by the use of the device and by employing a hand feed when the angle between the axis of link 39 and the direction of feed is too small to effectively control the turning movement of cutting tool 21 about the axis of pin 37 as a center.

For turning a concave surface similar to a dish or bowl, especially if it is to be turned in the end of a work piece or that surface which extends transversely of the bed of the lathe, the compound 14 and the cutting tool 21 carried thereby may be fed transversely of the lathe, either manually or mechanically, while at the same time, the longitudinal feed of the compound is disengaged so that the compound 14 is free to slide parallel to the ways 10 and 11.

Fig. 2 shows a modification of the device in which the link 39 is adjustable. When the link 39 is variable in length, adjustable bracket 33 has mounted in it a perforated link head 41 through which the pin 37 extends. At its outer end link head 41 carries a link rod 48 having a right hand thread on it. A plurality of link rods 48 of varying lengths are employed so that one approximately of the desired length may be selected. The opposite end of link rod 48 has screw threaded engagement with a turnbuckle 49. Turnbuckle 49 also has in it a cavity adapted to

receive one end 50 of a second link rod 53. End 50 has screw threads of the opposite pitch from those on the adjacent end of rod 48, in this case left-hand threads. The other end 51 of the second rod 53 has screw threads the same as those on rod 48, in this case right-hand. The rod 53 having the ends 50—51 may be short in length, for example, two inches. This rod fits into a perforated link head 52 adapted to be secured in the compound clamp 41 by pin 45 which passes through aligned holes in the compound clamp 41 and in the link head 52. The ends of turnbuckle 49 engage locknuts 54. The construction of Fig. 2 therefore provides a link which is readily adjustable to a wide variety of lengths.

Figs. 9, 10 and 11 show a second modification of the device, this modification being adapted to cut small radii. In this modification the adjustable bracket 55 is somewhat different in shape than the adjustable bracket 33 but it performs the same function. Adjustable bracket 55 has a hole at its end away from the headstock 12 in which hole is pivotally mounted a pin portion 56 of an eccentric, indicated generally at 57. Eccentric 57 has a crank or displaced portion 58 and a second pin portion 59. The compound clamp has a portion 60 which has the same function and corresponds to the compound clamp 41 although it is of slightly different shape. Compound clamp 60 has a hole in it in which the pin portion 59 of the eccentric is rotatably received. The axes of the pin portions 56 and 59 are offset by means of the crank or displaced portion 58 by an amount which is equal to the radius which is to be cut. Pin portion 60 has at its end a bolt portion 61 which is screw-threaded to receive a nut 62 on it. Likewise, pin portion 59 has a bolt portion 63 on it which is also screw-threaded to receive a nut 64. The adjustable bracket 55 and the compound clamp 60 are offset vertically so that they do not strike or contact one another but are free to ride over one another. This permits the distance between the axes of the pin portions 56 and 59 to be made as small as may be desired.

Summary

From the foregoing it will be seen that this invention provides a lathe or lathe attachment in which the cutting tool is mounted so as to be driven either manually or mechanically along one straight line while it is free to slide along a straight line at right angles to the first, there being provided, on a stationary part of the lathe, a pivot to which the cutting tool support is pivotally secured so that the cutting tool is constrained to move along a curved path whose radius is equal to the distance between the axes of the two pivots.

I claim:

1. In a lathe having the conventional bed provided with elongated ways and the conventional headstock adapted to receive and rotate the work-piece to be turned and the conventional tool-holding post movable manually or mechanically both transversely and longitudinally of said lathe bed, an attachment for cutting a curved surface having a large radius on a workpiece having a small diameter, including, an anchor base having a surface arranged to interfit with the ways of the lathe, an anchor clamp having a surface arranged to fit beneath the ways of the lathe, an anchor clamp bolt arranged for connection with said anchor base and said anchor clamp and adapted to secure said anchor base in a selected fixed position, an anchor bed having a perfo-

ration in it and firmly but detachably secured to said anchor base and having an elongated groove therein extending transversely of the bed of the lathe, a clamp bracket having a ridge extending from a surface thereof into the groove in said anchor bed, a bracket securing screw having engagement with said anchor bed and with said clamp bracket so as to secure said clamp bracket in a selected fixed position along said anchor bed, 10 a compound clamp having two perforations in it and a slot in one face thereof so that said compound clamp is adapted to engage with the tool holder of the lathe and to be secured to said tool holder by means of a bolt passing through one of the perforations in said compound clamp, a link having a pair of perforations in it, and a pair of pins passing through the perforations in said link and securing said link to said clamp bracket and to said compound clamp so that said compound clamp turns at the end of said link 15 about the pin in said clamp bracket as a center and thereby moves the tool holder of the lathe 20

in an arc whose radius is the distance between the centers of the pins.

2. The structure of claim 1 wherein the link consists of a pair of rods axially aligned and having threaded ends opposing each other and a turnbuckle threadably engaging the threaded ends of said rods so as to secure them together to make said link's length adjustable to the size of a desired radius.
